(57) **CLAIM**

The ornamental design for a paper bale device, as shown and described.

DESCRIPTION

FIG. 1 is a top perspective view of a paper bale device; FIG. 2 is a top plan view thereof;

FIG. 3 is a bottom plan view thereof;

FIG. 4 is a right side elevational view thereof, the left side elevational view being a minor image thereof;

FIG. 5 is a front elevational view thereof, the rear elevational view being a mirror image thereof;

FIG. 6 is a bottom plan view of the present invention showing the cords in an extended position with broken lines illustrating an environment of use; and,

FIG. 7 is a top plan view of the present invention showing the cords in an extended position with broken lines illustrating an environment of use.

The broken lines rendered in FIGS. 6 and 7 illustrate the environment of the claimed design and form no part thereof. While the paper bale device is in its extended position, the sides, front, and rear of the article form no part of the claimed design.
